FLUID SYSTEM

Lyle L. Mylcraine, Piper City, Ill.

Filed Apr. 10, 1958, Ser. No. 727,669

2 Claims. (Cl. 60—52)

This invention relates to a self-contained pressure differentiating and fluid metering device. It is described hereafter in connection with a hydraulic system of a farm tractor, in which it has particular practical application, but it is to be understood that the device has numerous other applications.

Modern farm tractors are customarily equipped with hydraulically operated draw bars. The hydraulic systems by which the draw bars are operated frequently are provided with pumps of such character as to circulate a large amount of hydraulic fluid at a relatively low pressure, for example ten to fourteen gallons per minute at thirty to twelve hundred pounds per square inch. Such a system has a number of advantages but it also has a serious disadvantage in that it cannot satisfactorily be used to operate other hydraulic equipment, such as a hydraulically operated power steering system, because such other equipment frequently operates at a different pressure. For this reason, it has been customary to install a separate and independent hydraulic system for the power steering at considerable expense, with a separate pump capable of delivering a relatively small amount of fluid at a relatively high pressure.

One of the objects of this invention is to provide a simple, compact device whereby a part of the energy of fluid which is moving under a head is utilized to pump a portion of the same fluid at a pressure different from the head under which the fluid was moving.

Other objects will become apparent to those skilled in the art in the light of the following description and accompanying drawing.

In accordance with this invention generally stated, a device is provided in which fluid moving under pressure is directed against vanes the effective area of which is selectively variable, in such a way that the vanes are caused to move and at the same time the effective area of some of the vanes is decreased. A portion of the fluid initially directed against the vanes is in turn impelled by the vanes with diminished area.

In the drawing, Figure 1 is a sectional view taken along the line 1—1 of Figure 2, showing a device constructed in accordance with one embodiment of this invention in a hydraulic system of a tractor, the hydraulic system being shown diagrammatically; and

Figure 2 is a sectional view taken along the line 2—2 of Figure 1.

Referring now to the drawing for an illustrative embodiment of this invention, reference numeral 1 represents a hydraulic system for a farm tractor, including a pump 2, a draw bar raising mechanism with the usual control valve and by-pass arrangement, all indicated diagrammatically at 3 in Figure 1, a pressure pipe 4 leading from the discharge side of the pump 2 and a return pipe 5 connected, by way of the draw bar raising mechanism 3, to the suction side of the pump 2.

In the hydraulic system 1, connected to the pressure pipe 4 at one side and to the return pipe 5 at the other, is a pressure differentiating and fluid metering device 10

constructed in accordance with one embodiment of this invention. The device 10 comprises a casing 12 and a rotor 50. The casing 12 is made up of a block 13 and a cover plate 14 bolted to the block 13 by means of 5 studs 15. The studs 15 take into tapped holes 16 in the block 13, passing through holes 17 in the cover plate 14. The block 13 is provided with an inlet passage 19, tapped to take a threaded end of the pressure pipe 4, and an outlet passage 20, tapped to take a threaded end 10 of the return pipe 5. Intermediate the inlet passage 19 and outlet passage 20 is a rotor cavity 22. The rotor cavity 22 is made up of a circular inner journal cavity 23, a circular outer journal cavity 24, and a vane receiving channel 25. The vane receiving channel 25 lies 15 between the journal cavities 23 and 24. It communicates with the inlet passage 19 and the outlet passage 20, between which it is substantially concentric with the journal cavities 23 and 24. It also connects the outlet passage 20 with a discharge passage 26. The discharge passage 26 has branches 27 and 28. A discharge pipe 30 is screwed into a threaded section of the discharge passage 26. Between the outlet passage 20 and the branch 27, the vane receiving channel 25 is also concentric with respect to the journal cavities 23 and 24. Between the 20 edge of the branch passage 27 nearest the outlet passage 20 and the edge of the branch passage 28 farthest from the outlet passage 20, the radial depth of the channel 25 decreases until at the edge of the branch passage 28 most remote from the outlet passage 20, the radii of the channel 25 and the journal cavities 23 and 24 are identical, as shown in Figure 1. In the quadrant between the branch passage 28 and the inlet passage 19, the radius of the channel 25 remains the same. A passage 36 in the block 13 communicates with the inlet passage 19 and 25 with the center of the inner journal cavity 23.

The rotor 50 is disc-shaped and is proportioned rotatably to fit within the journal cavities 23 and 24. In the embodiment shown, it is provided with eight radial slots or recesses 51 in each of which a vane 52 is slideably 40 mounted. Each vane 52 is biased outwardly by a spring 53 seated at one end in a bore 54 in the bottom of the slot 51, and at the other end in a recess 55 in the vane 52. An axial passage 58 in the rotor 50 communicates at one end with the passage 36 and at its other end with 45 branch passages 59 each connected with the bottom of a bore 54.

The vane receiving channel 25 is wide enough closely to receive the vanes 52 of the rotor 50. It is wider than the passages 19 and 20 along the area of communication with those passages as shown in Figure 2. The 50 radial depth of the channel 25 with respect to the journal cavities 23 and 24 and the rotor 50, between the inlet passage 19 and the outlet passage 20, is less than the length of the vanes 52 between their outside edges and the bottom of the recesses 55 against which the springs 54 bear. The radial depth of the channel 25 between the outlet passage 20 and the branch passage 27 of the discharge passage 26 is less than the radial depth of the channel 25 between the inlet passage 19 and the outlet passage 20, so that the volume of fluid which can be 55 accommodated by the channel 25 between successive vanes is less between the outlet passage 20 and the branch passage 27 than it is between the inlet passage 19 and the outlet passage 20.

In the embodiment shown, the discharge pipe 30 is connected with a power steering apparatus 35, indicated diagrammatically in Figure 1, from which the fluid flows through a differential valve 37, also shown somewhat diagrammatically in Figure 1. The differential valve shown 60 utilizes the bias of a spring 38 to maintain a greater pressure in the power steering system 35 than exists in the draw bar system. A steering system return pipe 70

39 connects the differential valve 37 with the return pipe 5.

In the operation of the illustrative embodiment shown, the system is filled with hydraulic fluid, generally an oily liquid. When the pump 2 is started, the fluid is forced through the pressure pipe 4. The fluid moves through the inlet passage 19 and, acting upon a vane 52 begins to rotate the rotor 50. A small part of the fluid will pass through the passages 36 and 58 into the branch passages 59, hence to the inside of the recesses or slots 51 where it will tend to force the vanes 52 outwardly, assisting the springs 53. As the rotor 50 begins to turn, and the fluid in the system begins to circulate, most of the fluid passing through the channel 25 between the inlet passage 19 and the outlet passage 20 will be discharged into the outlet passage 20, hence to the return pipe 5. A part of the fluid, however, will be forced into the channel 25 between the outlet passage 20 and the discharge pipe 26. This latter fluid is segmented between successive vanes, which have been moved partly inwardly but which bear snugly against the walls of the channel. When the leading of two successive vanes has passed the edge of the branch passage 27 nearest the outlet passage 20, the volume in the space between the blades decreases, because the depth of the channel decreases, so that the fluid between the vanes is forced through the branch passage 27 and, when the leading vane has begun to pass the branch passage 28, through the branch passage 28 into the discharge passage 26.

The pressure which is produced in the line 30, is dependent upon the differential valve 38, so long as the product of the pressure and the volume of fluid through the power steering system is less than the product of the pressure and the volume of fluid flowing through the channel 25 between the inlet passage 19 and the outlet passage 20, less the power losses due to friction of the rotor, line loss and the like. In the drawing of the illustrative embodiment shown, the radial depth of the channel 25 between the inlet passage 19 and the outlet passage 20 is about three times that of the channel between the outlet passage 20 and the branch 27. If the various losses to which reference has been made were disregarded the device should be capable of producing a pressure at the discharge passage 26 of slightly less than three times the pressure in the inlet passage 19, i.e., the pressure at which the fluid is delivered from the pump 2. In practice, in order to ensure free circulation of the fluid, a multiplication of one and one-half to two times is considered reasonable.

In practice, both the draw bar system and the power steering system will be provided with a reservoir of fluid under pressure.

The advantages of the device of this invention will be immediately apparent to tractor owners. With the aid of this simple device, the ordinary low pressure pump, which has ample capacity to handle both systems, can be utilized for both the draw bar operating system and a power steering system, at a small fraction of the cost of the installation of a totally separate power steering system and pump.

As a specific example of a device of this invention used with a hydraulic system on an ordinary farm tractor, in which a pump delivers ten to fourteen gallons per minute of hydraulic fluid at thirty to twelve hundred pounds per square inch pressure, the overall size of the block and cover plate can be six by six by two and one-half inches. The inlet passage 19 may have a bore of approximately seven-eighths of an inch. The rotor 50 may be approximately four inches in diameter and two inches wide, and the slots 51 approximately one and three-quarters of an inch deep. The vanes 52 may be approximately one and one-half inches long and approximately one and three-quarters to two inches wide. The channel 25 between the inlet passage 19 and the outlet passage 20 may be approximately one-half of an inch deep and

approximately one and three-quarters to two inches wide. The depth of the channel 25 between the outlet passage 20 and the branch passage 27 may be approximately three-eighths of an inch deep. The bore of the outlet passage 20 may be approximately seven-eighths of an inch, and of the discharge passage 26, one-half of an inch. A pressure of thirty to twelve hundred pounds per square inch may be produced by the differential valve 37, although, when the control valves to the drawbar raising cylinder and the power steering cylinders, not here shown, are in neutral position, the pressure regulator (by-pass) valves of the steering and drawbar raising mechanisms are normally arranged to open and allow the pump to circulate fluid at low pressure.

15 The bore of the outlet passage 20 can either be made smaller than the bore of the inlet passage 19 or a suitable choke can be used so that the combined volumes of the fluid delivered to the discharge passage 26 and the outlet passage 20 is the same as the volume of fluid delivered to the inlet passage 19. This ensures that the channel 25 between the outlet passage 20 and the discharge passage 26 is maintained full.

20 In the device described, the hydraulic fluid itself acts to lubricate the various parts. While the rotor fits closely within the rotor cavity, there is still enough clearance, for example from .001 to .005 inch, between the flat faces of the rotor disc and the flat face defining the bottom of the inner journal cavity 23 on the one side and the cover plate providing the bottom of the outer journal cavity 24 on the other, and between the peripheral surfaces of the rotor and journal cavities, to permit some of the fluid to get between them to accomplish the lubrication.

25 When liquids which have little or no lubricating qualities are to be handled, it may be necessary to mount the rotor on a shaft journaled in conventional sealed bearings which may be of any of numerous suitable kinds known to the art. The block, cover plate and rotor may be complementarily grooved to form races to receive ball bearings, or the rotor may be provided with stub shafts on either side, journaled in bearing cavities in the block and cover plate.

30 It can be seen that the device of this invention has numerous applications beyond the hydraulic system of a tractor. It can be used not only as a pressure differentiator but as a metering or proportionating device. If the channel 25 is kept filled, a volume of fluid bearing the same relationship to the total volume as the depth of the channel 25 between the outlet passage 20 and the discharge passage 26 bears to the depth of the channel 25 between the inlet passage 19 and the outlet passage 20 will be delivered to the discharge passage 26. Thus, water, oil, or other liquids which are pumped through a pipe under pressure, or gas, can be metered off by the use of this device.

35 Numerous variations in the construction of the device of this invention, within the scope of the appended claims will occur to those skilled in the art in the light of the foregoing disclosure. For example, the effective surface area of the vanes may be varied in ways other than making them slide radially within the slots in the rotor. If the vanes are made of rubber or other resilient material, they need not slide in radial slots in the rotor, but can be fixed on the periphery of the rotor. This arrangement is particularly useful in a device akin to the hydraulic ram.

40 Having thus described the invention, what is claimed and desired to be secured by Letters Patent is:

45 1. In a tractor having a hydraulically operated draw bar mechanism operating at one pressure and a power steering apparatus operating at a different pressure, said draw bar mechanism being supplied with fluid by a pump having a suction side and a discharge side, a pressure multiplying device by which the draw bar operating pump can be utilized to operate the power steering apparatus,

comprising a casing having a rotor cavity, an inlet passage to said rotor cavity connected to the discharge side of the pump, an outlet passage to said rotor cavity connected, by way of the drawbar mechanism, to the suction side of said pump and a discharge passage connected to the power steering system; a rotor rotatably mounted within said cavity, a plurality of vanes mounted in said rotor for radial sliding movement and extending closely but slideably within a channel in said cavity, said channel extending in an arc substantially concentric with the rotor between the inlet passage and the outlet passage and between the outlet passage and the discharge passage, said channel connecting said passages respectively, the depth of said channel between the outlet passage and the discharge passage being substantially less than the depth of the channel between the inlet and outlet passages and the depth of the channel between the discharge passage and the inlet passage being substantially less than the depth of the channel between the outlet and discharge passages.

2. In a system wherein fluid flows in a conduit connecting a high pressure area to a low pressure area, a device of the character described, wherein the kinetic energy of the flowing fluid is utilized to multiply the pressure of a portion of the fluid itself, said device consisting of a casing having a rotor cavity defined by a wall, an inlet passage communicating with said fluid conduit on the high pressure side and with said rotor cavity, an

outlet passage communicating with said fluid conduit on the low pressure side and with said rotor cavity, and a discharge passage communicating with said rotor cavity, said outlet passage lying between the discharge and inlet passages; a rotor rotatably mounted within said rotor cavity, and vanes mounted on said rotor, said vanes being biased to bear against the wall defining the rotor cavity and adapted to move in response to variations in the contours of said wall, said wall being substantially concentric with the rotor between the inlet passage and the outlet passage, and between the outlet passage and the discharge passage and defining a channel with said rotor, the cross sectional area of the channel between the inlet and outlet passages being greater than that between the outlet and discharge passages, and said rotor and wall defining a constricted section between the discharge passage and the inlet passage of less cross sectional area than that of the channel between the outlet passage and the discharge passage.
